UNITED STATES PATENT OFFICE.

WILLIS GLAZIER, OF NEWARK, NEW JERSEY.

PAN FOR SHAPING HAT-BRIMS.

SPECIFICATION forming part of Letters Patent No. 717,839, dated January 6, 1903.

Application filed October 6, 1902. Serial No. 126,003. (No model.)

To all whom it may concern:

Be it known that I, WILLIS GLAZIER, a citizen of the United States, residing at Newark, in the county of Essex and State of New Jersey, have invented and produced a new and original Improvement in Pans for Shaping Hat-Brim; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to give a more perfect and uniform shape and finish to the brims of felt hats; to facilitate the work of shaping and finishing said brims; to avoid the necessity of ironing the said brims 20 after the same have been subjected to the hot sand used in connection with the shaping-pan, as heretofore required, and to secure other advantages and results, some of which may be referred to hereinafter in connection with 25 the description of the working parts.

The invention consists in the improved shaping-pan for giving form or shape to brims of felt hats and in the arrangements and combinations of parts of the same, all substantially as will be hereinafter set forth, and finally embraced in the clauses of the claim.

Referring to the accompanying drawings, in which like letters of reference indicate corresponding parts in each of the several views, 35 Figure 1 is a plan of the improved shaping-pan. Fig. 2 is a side elevation of the same, showing the parts of the same in the position assumed before application to the brim, the "bag" of said pan being broken away and in 40 partial section; and Fig. 3 is a section of the device, taken on line α of Fig. 1, showing more clearly the parts after they have assumed their pressing relation to the hat and its brim upon a hat-flange underneath the pan.

45 In said drawings, a indicates a hat-flange centrally open to receive the body of the hat and shaped at the top and upper parts of the sides to give shape to the brim, and b indicates a felt hat arranged on said flange, the 50 brim c of said hat being turned over the upper edges of the surfaces of said flange.

d indicates the pan, adapted to receive the

heated sand e , the said pan embodying my improvements. Said pan consists of two sections f g , hinged together at opposite sides 55 of the pan, as at h . The section g comprises a semicircular top plate i , to the convex outer edge of which is secured a depending side plate j , the ends or ears k of which project horizontally beyond the chord-like edge l of 60 the said semicircular top plate i to receive the pivotal pins connecting the two sections. The section f also consists of a top plate and side plate. The bottom edges of the said side plates are formed on curved lines extending 65 downward from the lower edges of the ears k toward the center of the plate, the said center of the side plate being of considerable width for a purpose hereinafter described.

The section f of the pan, pivoted to the 70 section g , is also provided with comparatively narrow ears, which overlap the ears of the said section g , and with a wide central part or cheek m , lying opposite the wide central part or cheek m of the opposite section. The 75 top plate i of this section f is somewhat wider than that of the said section g and is bent in lines concentric with the hinge-pins, as at n , the bent flange n of the said top plate f extending underneath the top plate of section 80 g three or four inches, more or less, so that as the said sections turn on the said hinge-pins to the position shown in outline in Fig. 2 and in full line in Fig. 3 there will be no opening formed at the top of the pan through which 85 the sand may escape. At a suitable point at the top of one of said sections I have formed a mouth or feed-opening o to permit the insertion of the sand, the said opening under certain conditions being closed by a cork or other suitable stopper. Under some conditions it may remain open and serve as a vent. The top of one of the sections is also provided with a handle p , by means of which the pan may be manipulated with convenience when, filled 90 with sand, it is being applied to the hat or removed therefrom.

The top of the pan is also provided at or near its periphery with four (more or less) 95 eyes q to receive chains, wires, or other suitable connection adapted to extend over a pulley or pulleys, whereby the pan may be drawn up and away from the hat with convenience. At the lower outer edges of the

sections the same are provided with flanges or stays *r*, adapted to hold the flexible cloth or bag in place over the open bottom of the pan when the edges of the said cloth or bag 5 are tied around the periphery of the said pan. The cloth or bag *s* is of a size sufficient to spread across the open bottom of the pan with more or less looseness and at its edges extend over the stays *r*, so as to be properly 10 tied by means of a cord.

It will be obvious upon examination of Figs. 2 and 3 that the pan at its bottom edges presents in side elevation deep opposite recesses between the wide downwardly-extending 15 cheeks *m*.

The flexible bag being stretched across the open mouth at the bottom of the pan assumes somewhat of the same shape in side elevation. The sand being inserted through the 20 feed-opening *o* or otherwise, and the said pan being elevated by means of the wires or chains or similar connections, (not shown,) the draft upon the opposite sides of the pan causes the sections to assume the positions of Fig. 2, in 25 which case the cheeks of the sections lie approximately vertical. Upon lowering the pan into engagement with the bat resting upon the flange *a* the bag at the center of the pan first engages the hat lying beneath the said 30 center in about the vertical plane of the hinge-pins. The weight of the sand lying at the inside of the cheeks of the pan causes said cheeks to automatically draw together to the position shown in outline in Fig. 2, and 35 thus the heated sand is caused to press beneath the inwardly-curved hat-brim, so that the said brim is not only pressed downward by the weight of the sand and laterally inward toward the center of the hat, but to 40 some extent upward beneath the said inwardly-turned edges of the hat-brim, and because of this upward pressure the hat-brim is completely shaped by the sand, and consequently further shaping by means of heated 45 irons or the like is rendered unnecessary.

Having thus described the invention, what I claim as new is—

1. The improved shaping-pan for hats, comprising pivotal sections provided at the top 50 with a feed-opening and being open at the bottom, and a bag fastened across the bottom of said pan, said bottom being provided at opposite sides with broad cheeks adapted to drop by gravity and cause the bag to pass beneath 55 a hat-brim lying upon a hat-flange.

2. The improved shaping-pan for hats herein described, comprising pivotal sections hav-

ing comparatively narrow overlapping ears and wide cheeks and open bottoms, a bag extending across the bottom of said sections 60 from cheek to cheek thereof, and a filling of sand the weight of which lying adjacent to said cheeks is adapted to cause said sections to turn on their connecting pivots when the center of the bag with the sand therein engages the top of a hat-flange or the hat thereon, whereby the cheeks are caused to draw together and lie beneath the curved hat-brim, substantially as set forth.

3. The combination with the sections of the 70 shaping-pan having an open bottom, of a bag closing the open bottom of said pan, a handle at the top of said pan, and means for preventing the said sand from escaping at the top of said pan, substantially as set forth. 75

4. The combination of the sections comprising semicircular top plates and side plates fastened at the convex edges of said semicircular plates, one of said top plates extending underneath the other of said top plates, 80 the underlying extension of the top plate being curved concentric or approximately concentric with the pivotal pins, whereby the said sections may turn on said pins, without forming an opening in the top plates, sub- 85 stantially as set forth.

5. The combination with the semicircular top plates, of side plates secured to the convex edges thereof, the said side plates forming at their opposite overlapping extremities 90 narrow ears through which pivotal pins extend, and having between said narrow pivotal ears, wide cheeks, the said cheeks lying beneath the pan, and a bag fastened over the open bottom of the pan, substantially as set 95 forth.

6. A hat-shaping pan comprising hinged sections open at the bottom and providing side walls to retain sand, and a flexible bag closing said open bottom and adapted to support the sand. 100

7. A hat-shaping pan having hinged sections open at the bottom and providing side walls to retain sand, a bag extending across said open bottom, and means for securing the 105 margins of said bag to said sections to prevent the escape of sand.

In testimony that I claim the foregoing I have hereunto set my hand this 27th day of September, 1902.

WILLIS GLAZIER.
